UNITED STATES PATENT OFFICE.

JOSEPH A. STEINMETZ, OF PHILADELPHIA, PENNSYLVANIA.

MEANS FOR PROTECTING VESSELS AGAINST SUBMARINES.

1,253,295.

Specification of Letters Patent. Patented Jan. 15, 1918.

Application filed October 13, 1917. Serial No. 196,427.

To all whom it may concern:

Be it known that I, JOSEPH A. STEINMETZ, a citizen of the United States, and resident of Philadelphia, in the county of Philadelphia and State of Pennsylvania, have invented certain new and useful Improvements in Means for Protecting Vessels Against Submarines, of which the following is a specification, reference being had thereto in to the accompanying drawing.

Since water is incompressible and resists instantaneous movement like a solid of equal weight, the explosion of a submerged torpedo cannot displace the water mass in and 15 below the plane of explosion, but can and does tear out and shoot upward, with most destructive force an inverted water cone having its apex at the point of explosion. The object of this invention is to cause approaching torpedoes to explode at such point that no portion of the attacked ship lies within the cone or most dangerous region, and to cause this explosion by ship-borne devices which offer great resistance to rolling 20 motion of the ship and but little resistance to its other movements.

In the accompanying drawings,

Figure 1 is a side view of a vessel provided with one form of my devices.

Fig. 2 is an end view of the same structures.

Fig. 3 is an end view showing a different form of the attachment.

Fig. 4 is a view similar to Fig. 1 showing 35 a third form of the attachment.

Fig. 5 is a section on the line 5—5, Fig. 4.

Fig. 6 is a partial plan view of the devices of Fig. 1.

In these views, 6 represents the hull of a 40 ship having secured to each side slightly below the water line a very large straight steel tube 7, preferably divided transversely into sections, open at its ends and extending nearly from end to end of the hull. The 45 diameter of each tube is great enough to protect the greater part of the submerged portion of the hull from near the water line to the region of the keel so that no torpedo moving horizontally can strike the ship at 50 any point below the body of the hull, where lifting force would be fatal, and, while of comparatively thin metal, the tube is rigid enough to cause the explosion of any ordi-

nary contact-detonated torpedo which may strike it, and such explosion will occur at 55 such distance from the ship as to make serious injury to the latter improbable. The tubes being of substantially uniform diameter and open at the ends they offer comparatively small resistance to advance in the 60 water, even when provided with internal braces 8, and their form makes it a simple matter to secure them rigidly in place although they are light. It is to be noted that when in place they virtually broaden the 65 hull very materially and have a steady effect many times that of "fin keel" construction.

Instead of using cylindrical tubes, tubes 9, Fig. 3, may be formed with the hull as one 70 side, the tube sheets having their widely separated upper and lower margins 10, 11, attached to the hull and bodies of the sheets being carried outward and returned by smooth curves. In this form also, the tubes 75 may have internal braces 12, 13, preferably located in but few planes to minimize resistance to advance in the water.

If desired, the tubes of either form may have their ends closed and be filled with air, 80 and may be divided into compartments by partitions 15, Fig. 4, or the tubes may be divided into independent slightly separated aligned sections 16, 17, Figs. 4, 5. This construction gives an air cushion and adds materially to the buoyancy of the ship and to the difficulty of sinking it, but it has a greater retarding effect upon the ship, even when the tube conforms to the hull's curvature and the forward section is made wedge- 90 like as at 20, Figs. 4, 5.

What I claim is:

1. The combination with the hull of a ship of terminally open, internally substantially unobstructed approximately horizontal tubes 95 of approximately uniform cross section fixed to the sides, respectively, of the hull and extending from the region near the water line to the region near the keel and nearly from stem to stern of the vessel. 10

2. The combination with the hull of a ship, of large approximately horizontal open tubes secured to the sides of the hull, respectively, and extending nearly the length of the hull and from near the level of the water 10 line to the region of the keel, said tubes

being divided into several independent abutting sections.

3. A ship's hull having the greater part of its submerged portion widened laterally by relatively light tubular structures of metal internally open from end to end rigidly fixed to the hull and projecting, along

nearly the whole length of the ship, to a distance approximately equal to their vertical extent.

In testimony whereof I hereunto affix my signature. 10

JOSEPH A. STEINMETZ.
